UNITED STATES PATENT OFFICE.

THEODOR HEINEN, OF SOLINGEN, GERMANY.

APPARATUS FOR DEVELOPING PHOTOGRAPHIC PLATES BY DAYLIGHT.

1,205,893.

Specification of Letters Patent. Patented Nov. 21, 1916.

Application filed June 9, 1915. Serial No. 33,152.

To all whom it may concern:

Be it known that I, THEODOR HEINEN, a subject of the German Emperor, and resident of Solingen, Germany, have invented 5 certain new and useful Improvements in Apparatus for Developing Photographic Plates by Daylight, of which the following is a specification.

This invention relates to an improved 10 apparatus for developing photographic plates, according to which the plate to be developed may be put by daylight from its holder into the developing receptacle, in which it can be inspected from both sides 15 during its development.

The accompanying drawing shows the improved apparatus in Figures 1 and 2 in a sectional side view and edge view respectively.

20 In a casing *a*, which is open at the top, a glass receptacle *b* for the reception of the developing liquid is located, which is also open at the top and at its bottom provided with a closable outlet *c*. On its two opposite sides, the casing *a* is provided with cut-away portions *d*, *d'* respectively, which are closed by red glasses *e*, *e'*. Over the open-ended top part of the casing *a* a hood *f* is located which on its two opposite sides 25 has also two cut-away portions *g*, *g'* which, upon the hood being entirely lowered over the casing, correspond with those in the casing.

30 In the interior of the hood *f*, a frame *l* is suspended from a guide *m* and in connection with a pin *n* projecting from the casing. By means of said pin, the frame *l* can be so adjusted that it is placed either directly above the open top end of the glass 35 receptacle *b* or upon the cut-away portion *g* in the hood *f*. The pin *n* is fitted with a catch *p*, against which a slide *r* in the frame *l* is pressed by action of a spring *s*.

To use the developing apparatus, first the 40 hood *f* is so located over the casing *a* that the cut-away portions *g*, *g'* lie above the upper edge of the casing *a*, and the frame *l* is moved upon the cut-away portion *g*, in which position it bears with a spring *v* 45 against a projection *w* of the hood and is thus held in the desired position. The pin *l*

can be so turned in this position of the frame *l* that the catch *p* liberates the slide *r*, in which case the latter is pressed upward by spring *s*, whereby the distance between 55 the foot end of the frame *l* and the slide *r* becomes greater than the length of the plate to be developed. Thereupon, the cut-away portion *g'* is closed by means of a slide *i* inserted in a guide *h* of the same, 60 while the holder with the plate to be developed is so introduced in a guide *k* in front of the cut-away portion *g* that after removal of the cover of the holder the plate lies opposite to the cut-away portion *g*. In 65 the holder, spring members or the like are arranged in a way known in the art, by which the plate is ejected and pressed through the cut-away portion *g* into the frame *l*, between the front end of which and 70 the slide *r* the plate is fixed by turning the pin *n* into its initial position. In the hood *f* the plate is entirely separated from the daylight. Upon the frame *l* being then shifted directly above the open top end of the glass 75 receptacle *b*, the hood is lowered over the casing whereby the plate is put into the glass receptacle *b*. After removal of slide *k*, the plate and its development can be inspected from outside through the red glasses 80 *e*, *e'* from both sides of the same. The filling of the glass receptacle *b* takes place through a supply-pipe *t* arranged on the top end of the hood, and its emptying through the outlet *c*.

85 What I claim, is:—

Apparatus for developing photographic plates by day-light, comprising in combination, a casing having an open top end and cut-away portions in its two opposite sides, 90 a red glass in each cut-away portion, a glass receptacle in said casing for the reception of the developing liquid having also an open top end, a closable outlet at the bottom end of said glass receptacle, a hood movably 95 located over the open top end of said casing and having also cut-away portions in its two opposite sides corresponding with those in said casing upon the hood being entirely lowered over the latter, a slide to close one 100 cut-away portion in said hood, a frame movably suspended in said hood for the recep-

tion of the plate to be developed and adapted to be located either directly above the open end of said receptacle or upon the other cut-away portion in said hood, and a supply-pipe at the top end of said hood, substantially as and for the purpose set forth.

In testimony whereof I have hereunto set my hand in the presence of two subscribing witnesses.

THEODOR HEINEN. [L. S.]
